UNITED STATES PATENT OFFICE.

EDWIN E. ANGELL, OF BOSTON, ASSIGNOR OF ONE-HALF TO E. B. WELCH,
OF CAMBRIDGE, MASSACHUSETTS.

HEAD-HOLDER FOR CAN-HEADING MACHINES.

SPECIFICATION forming part of Letters Patent No. 416,537, dated December 3, 1889.

Application filed May 20, 1889. Serial No. 311,364. (No model.)

To all whom it may concern:

Be it known that I, EDWIN E. ANGELL, of Boston, in the county of Suffolk and State of Massachusetts, have invented certain new and useful Improvements in Head-Holders for Can-Heading Machines, of which the following is a specification.

This invention relates to machines for applying flanged heads to cylindrical can-bodies, and particularly to the mechanism shown in my pending application for Letters Patent filed February 18, 1889, Serial No. 300,247, said mechanism including a holder or carrier to receive a flanged can-head, jaws pivotally connected to said holder to hold a can-head therein, mechanism for closing and opening said jaws to cause them to alternately hold and release the can-head, and mechanism for reciprocating said holder and giving it a tipping movement, whereby the holder is first moved toward a suitably-held can-body and caused to apply the head thereto, and is then removed from the can-body, leaving the head thereon, the jaws, which were closed on the can-head during the forward movement of the holder, being opened after the application of the can-head, so that on the returning movement of the holder they pass over the applied head without contact with it.

The present invention consists in certain improvements in the means for opening and closing the head-holding jaws, which I will now proceed to describe and claim.

Of the accompanying drawings, forming a part of this specification, Figure 1 represents a side elevation of the head-applying mechanism above referred to provided with my improvements. Fig. 2 represents a top view of the same. Figs. 3 and 4 represent, respectively, a side and top view of the head holder or carrier and portions of the supporting and operating devices. Fig. 5 represents a section on line 5 5, Fig. 3.

The same letters of reference indicate the same parts in all of the figures.

In the drawings, *j* represents the head holder or carrier, in the forward end of which is a cavity *p*, formed to receive a flanged can-head. In said cavity is a plunger *q*, attached to a rod *r*, which is adapted to slide longitudinally in said holder and in a guide *s*,

which is formed on a swinging frame *s*, said frame being pivoted at 3 to an arm 2, affixed to a slide *w*, which is fitted to move between guides *y y* on the supporting-frame. The 55 holder *j* is fitted in a socket in the frame *s*, and said frame, with the slide *w*, is moved longitudinally to carry the holder *j* and the head-holding jaws thereon toward and from a can-body to be headed, said body being 60 held for the heading operation by suitable clamps or holders, as shown in my application for patent for can-heading machines filed February 18, 1889.

The devices thus far described, as well as 65 other parts not here specifically referred to, are the same in their construction and operation as the parts similarly lettered in the drawings of my former application, Serial No. 300,247.

m' m' represent the head-holding jaws, which are formed on the forward ends of levers *m m*, said levers being pivotally connected by bolts *k k* to ears on the holder, as in the application last referred to.

A A represent springs, which are placed in sockets in the holder *j*, and bear against the forward ends of the levers *m m*, pressing said ends and the jaws *m' m'* thereon outwardly, so that said jaws stand normally in their opened 80 position or separated so that they will pass over a can-head without contact therewith.

The rear ends of the levers *m m* are curved inwardly and bear against the conical or tapering forward end of a collar *B*, which is 85 fitted to slide on the reduced rear portion of the holder *j*. Said collar is provided with a peripheral groove *C*, which receives studs *D* on the forked ends of the lever *E*, which lever is pivoted at *F* to a fixed ear *G*, attached to the supporting-frame, and has at its lower end a trundle-roll entering a cam-groove *H* in a roll *I*, affixed to the shaft *f*, which actuates the other parts. The rotation of said shaft causes the cam-groove *H* to 95 oscillate the lever *E*, said lever moving the collar *B* back and forth. When the collar is moved forward or toward the outer end of the holder *j*, its tapered end is inserted between the rear ends of the levers *m m* and forces said 100 ends outwardly, forcing inwardly the opposite ends of said levers and the jaws *m'*, and caus-

ing said jaws to hold a can-head in the cavity p . When the collar is moved backward, it is withdrawn from between the levers $m m$, and the springs $A A$ are allowed to throw the jaws 5 $m' m'$ outwardly to their normal positions.

The described movements of the collar B are timed so that the jaws are forced inward or closed prior to the insertion of a can-head in the cavity p , remain closed during the forward movement of the holder, are opened just before the backward movement of the holder, and are held open until the jaws pass over the applied head.

I claim—

- 15 1. The combination of the can-head holder having the head-receiving cavity in one end, the levers pivoted to the head at opposite sides thereof, the jaws on the outer ends of said levers arranged to project partly over the said cavity, springs whereby the jaws are normally pressed outwardly, and mechanism for forcing outwardly the inner ends of said levers and thereby closing the jaws, as set forth.
- 20 2. The combination of the can-head holder

having the head-receiving cavity, the levers $m m$, pivoted to opposite sides of the head, the jaws on the outer ends of said levers, the springs whereby said jaws are normally opened, the tapered collar interposed between the inner ends of said levers, and means for reciprocating said collar, as set forth. 3c

3. The combination of the can-head holder, the levers $m m$, pivoted thereto, the jaws on said levers, the springs whereby said jaws are normally opened, the tapered collar arranged to act on said levers and thereby close the jaws, the forked lever pivoted centrally to a fixed support and engaged at one end with said collar, and a positively-rotated cam engaged with the other end of said lever, as set forth. 35

In testimony whereof I have signed my name to this specification, in the presence of two subscribing witnesses, this 13th day of May, A. D. 1889.

EDWIN E. ANGELL.
